UNITED STATES PATENT OFFICE.

FRANCIS ARTHUR MILLS, OF METHUEN, MASSACHUSETTS, ASSIGNOR OF
ONE-HALF TO GROSVENOR B. EMMONS, OF SAME PLACE.

PICKER-STICK BUFFER FOR LOOMS.

SPECIFICATION forming part of Letters Patent No. 669,760, dated March 12, 1901.

Application filed October 23, 1900. Serial No. 34,082. (No model.)

To all whom it may concern:

Be it known that I, FRANCIS ARTHUR MILLS, a citizen of the United States, residing at Methuen, in the county of Essex and State of Massachusetts, have invented certain new and useful Improvements in Picker-Stick Buffers for Looms, of which the following is a specification.

The invention hereinafter set forth is directed to the attainment of new and advantageous results in checks or buffers for the picker-stick motion of looms; and the invention resides in a strap buffer device for the cam-actuated impact of the picker-stick, whereby to throw a more accurate shuttle and to regulate the flight of the shuttle and prevent the destructive and deranging effects of the picker-stick motion in throwing the shuttle through the open shed, and in the claims, concluding this specification the novel features of the strap-buffer will be set out.

The accompanying drawings illustrate my new strap-buffer in its use with the picker-sticks of looms, and referring to these drawings—

Figure 1 shows in side view, enlarged, the strap-buffer for the cam-actuated blow of the picker-stick. Figs. 2 and 3 are respectively vertical and horizontal sections of the same, the latter looking at the under side of the race-lay. Fig. 4 is a cross-section of the same, taken through the mounting of the spools of the strap-buffer. Fig. 5 is a sectional view of the adjusting device for the buffer-strap.

The picker-sticks 1.1 are shown mounted and actuated in the usual way.

The provision which I have made for cushioning the cam-actuated or inward blows of the picker-sticks consists of strap-buffers 12 and a pair of springs 13 13, separately connecting the ends of the strap. The straps are mounted each at one end of the lay 5 upon a pair of spools 14 14 on the under side of the race-lay at the inner ends of and on each side of the slots in the race-lay, within which slots the picker-sticks have their to-and-fro movements. The strap crosses around the spools across the path of the picker-stick, so that each end of the strap passes around a spool

and extends therefrom parallel to each other 50 some distance from the spools and toward the end of the race-lay, and therefore at right angles to the blow-receiving side of the strap upon which the blow is delivered between the ends of the strap and will force it in a direction away from the spools to the extent shown in Fig. 3 from the dotted lines, at which position of the strap the impact is delivered. The strap is made double and passed as a single strap around the spools, with its doubled 60 ends 15 15 each connected to a spiral spring, the other ends of which are connected to brackets 16, fixed to and depending from the race-lay. This connection of each end of the strap with a separate spring gives a free yielding function at both ends under the impact of the picker-stick. This impact forces the strap in a direction away from the spools, and it is the provision of the pair of springs with their tension adjusted equally on each end of 70 the strap that gives the best cushioning effect on the picker-stick and causes the strap to return to its normal position. A simple way of mounting the spools is seen in Fig. 4. A bolt 17, screwed into a bracket 18, fastened to the front side of the lay, serves as the mounting-stud of one of the spools, and a bolt 19, passed through a hole in the lay at its rear side, supported by a washer 20, holds the other spool. At the end of the race-lay 80 brackets 16 depend and form the connections for the springs. For this connection a screw 21 passes through a non-threaded hole in the bracket 16 and engages a central bore in a conical block 22, around which the end of the 85 spring is wound and bound. By means of these bolts 21 each end of the strap can be adjusted and the bolt locked by jam-nuts 23 to the bracket 16, while a nut 24 locks the bolt to the conical block. The connection of the springs 90 to the looped ends of the buffer-strap is made by yokes 25, looped into the doubled ends of the buffer-strap and formed with a conical block 26, upon which the end of the spring is wound and bound. By loosening the jam-nuts and turning the bolts the tension of the 95 springs can be increased or diminished. The connection of each end of the strap with a

spring and the delivering of the impact so as to force the strap in a direction away from the spools will cause very little strain upon the same and causes the latter to have a free 5 rolling upon their supports in one direction under the impact of the picker-staff and in the other direction under the tension of the springs. This relieves the spools of the great 10 strain of the picker-stick blows and prevents wear of the strap and the rolls. The pair of 15 springs gives equal and positive tension on each end of the strap, so that whatever the adjustment of the tension of the springs the strap will always yield equally at both ends 20 with a perfect yielding buffer function upon and with the picker-stick. The connection of the spring with the ends of the race-lay allows the use of long springs, which are more 25 elastic and easily adjusted and do not interfere with the mechanism on the race-lay. The provision of the loops connecting the strap and springs brings the line of the tension 30 immediately of the width of the strap and preserves the proper relation of these parts with the spools and keeps both parts of the 35 double strap taut and in place.

Provision is made for cushioning the blows of the shuttle at the end of its flight across the lay by means of pneumatic rubber buffers 27, 27, depending from each end of the race-lay in the path of the picker-sticks. These rubber buffers are each composed of 35 an impact-surface of less than half a sphere, a suitable seat and casing 28 therefor, forming an air-chamber 29 of fixed area below or behind said seat, and an unvalved opening 30 from said chamber, whereby the blow of the shuttle and picker-stick is delivered without resilient effect upon the pneumatic buffer, 40 and it is this non-resilient action which prevents the rebound of the shuttle in its flight against the picker and picker-stick. For the proper impact of the picker-stick upon the rubber buffers they are provided with convex striker-bunters 31, arranged so that the impact is central with the buffer, the blow giving practically a dead effect on account of the air being driven out of the chamber 45 through the vent.

50 The shuttle is thrown and received in the usual way by the picker-stick, while a yielding stuffed bunter 33 on the same side of the picker-stick as the picker serves to deliver the cam-actuated shuttle-blow of the picker-stick upon the strap-buffer, so that both the bunter and the strap cushion the blow in throwing the shuttle.

Obviously the employment of the doubled 55 strap mounted as a single strap upon the loose spools not only gives the advantage of always supporting the impact layer of the strap by its doubled layer, but this construction gives the important advantage of allowing the strap to be reversed upon its mounting-spools to present either layer thereof to receive the impact of the picker-stick. The

layers of the strap can also be changed to change the impact-surface by rolling the looped ends of the strap through the loops by which it is connected to the springs. 70

I do not claim herein this pneumatic rubber buffer, as such matter is made the subject of a separate and distinct application for a patent, filed by me April 19, 1900, Serial No. 13,496, and on which Patent No. 664,816 was granted December 25, 1900. 75

I claim—

1. A buffer for the cam-actuated or inward throw of the picker-stick comprising a pair of spools loosely mounted on each side of the path 80 of the picker-stick, an endless strap doubled, its layers in contact with each other, its ends terminating in loops and a spring giving the proper tension on each looped end of the strap whereby both layers of the strap one supporting 85 the other are caused to move together on the spools as a single strap with the shuttle-driving impact of the picker-stick and in the return of the strap to its normal position.

2. In a loom the combination of the picker-stick, and the race-lay, with a buffer for the cam-actuated throw of the picker-stick comprising a pair of freely-mounted spools, an endless strap doubled its layers engaging the spools as a single strap the loops formed by 95 its ends lying between the spools and the end of the lay, a pair of coil-springs engaging each looped end of the strap to give equal tension on its layers and screw-bolts on the lay entering and connecting the springs in 100 the longitudinal line thereof.

3. A buffer for the cam-actuated or inward throw of the picker-stick comprising a pair of spools loosely mounted on each side of the race-lay slot, an endless strap doubled, its 105 layers in contact with and supporting each other on the spools, the strap terminating in looped ends, in combination with loops freely engaging each looped end of the strap, and a spring engaging each loop, whereby the doubled strap is free to be moved in either direction through the spring-engaging loops to change its point of contact by changing the supporting relation which one layer of the strap gives to the other. 110

4. In a loom, the combination of a picker-stick, the race-lay and a shuttle, with a buffer for the cam-actuated throw of the picker-stick, comprising a pair of spools mounted on each side of the picker-staff slot in the race-lay, an endless strap doubled as a single strap crossing around the spools, a loop engaging the looped ends of the doubled strap, a coiled spring secured to the loop, brackets on the end of the lay, each having an unthreaded hole, a screw-bolt passing through the bracket-hole, a hub bound in the end of the spring and having a central screw-threaded bore for engaging said bolt, and jam-nuts on the bolt between the brackets and the said hub. 125

5. In a loom and in combination with the picker-stick and the race-lay, a buffer-strap 130

for the cam-actuated or inward throw of the picker-stick comprising a pair of freely-mounted spools an endless strap doubled, its layers engaging the spools as a single strap, one layer supporting the other, a pair of springs connecting the looped ends of the doubled strap, and the strap adapted to be reversed to change its layers in relation to

the spools and to the impact of the picker-stick.

In testimony whereof I affix my signature in presence of two witnesses.

FRANCIS ARTHUR MILLS.
